UNITED STATES PATENT OFFICE.

ALBERT D. MEAGLEY, OF BOWLING GREEN, OHIO.

MINNOW-NET.

1,084,892.

Specification of Letters Patent. Patented Jan. 20, 1914.

Application filed May 8, 1913. Serial No. 766,448.

To all whom it may concern:

Be it known that I, ALBERT D. MEAGLEY, a citizen of the United States, residing at Bowling Green, in the county of Wood, 5 State of Ohio, have invented certain new and useful Improvements in Minnow-Nets; and I do hereby declare the following to be a full, clear, and exact description of the invention, such as will enable others skilled 10 in the art to which it appertains to make and use the same.

The present invention is directed to improvements in minnow nets, and has for its object to so construct a device of this character 15 that the same can be lowered in the water so as to trap the minnows.

A further object of the invention is to so construct a device of this character that when drawn from the water the possible escape 20 of the trapped minnows is prevented.

With these and other objects in view, this invention resides in the novel features of construction, formation, combination and arrangement of parts to be hereinafter more 25 fully described, claimed and illustrated in the accompanying drawing, in which:—

Figure 1 is a perspective view of the net. Fig. 2 is a sectional view on line 2—2 of Fig. 1. Fig. 3 is a similar view on line 3—3 30 of Fig. 1.

Referring to the drawing, the numeral 1 designates a frame, which consists of a plate 2, the same being provided with radially arranged slots 3, and alined with each slot is 35 a perforation 4 which is engaged by the hooked ends 5 of the arms 6 when their portions adjacent the hooks 5 are engaged in the slots 3.

The arms 6 are formed from resilient 40 wire and are bent intermediate their ends to provide eyes 7, said arms also being provided at their extreme lower ends with eyes 8.

Upper and lower frames 9 and 10 are 45 provided, the lower frame being greater in size than the upper frame. The frames are formed from cord, or if desired light wire may be used.

The upper frame 9 has connected thereto 50 snap hooks 11, similar hooks 12 being connected to the lower frame 10, whereby when the snap hooks 11 and 12 are engaged in the eyes 7 and 8, respectively, the frames will be stretched, owing to the resiliency of 55 the arms 6, and held in rectangular form.

The netting 13 has its upper edges se-

cured to three of the sides of the upper frame 9, and their lower edges secured to a corresponding number of sides of the lower frame 10, said netting terminating below the 60 lowermost frame in skirts 14, which have their edges provided with sinkers 15 so as to facilitate the entrance of the skirts into the water.

A hood 16 is provided and is formed 65 from netting 17 and has the upper edge of its mouth connected to one side of the upper frame 9 and the sides of its mouth connected to the parallel sides of the netting 13, while the lower edge of said mouth is provided 70 with sinkers 18. The lower edge of the mouth is suspended by one of the sides of the lower frame 10 by cords 19. It will be noted that the lower edge of the mouth of the hood is on a plane with the lower edges 75 of the skirts 14, so that when minnows are trapped by the skirts and netting 13, and the entire device moved quickly in one direction the minnows will pass into the hood through its mouth, during which time the 80 hood will, by the resistance offered by the water, remain extended until the device is lifted to remove the minnows.

What is claimed is:—

1. A minnow net comprising a frame having resilient arms, upper and lower flexible frames supported by said arms, netting having its upper edges connected to certain of the sides of the upper frame and its lower edges connected to certain of the sides of the lower frame, said netting having its lower edge terminating in a weighted skirt, and a hood consisting of netting having the upper edge of its mouth connected to one of the sides of the upper frame and its sides 85 connected to the netting supported by the sides of the upper and lower frames, said hood having the lower edge of its mouth suspended below one of the sides of the lowermost frame and having sinkers connected thereto, as and for the purpose set forth.

2. A minnow net comprising a frame consisting of a plate, said plate having radially arranged slots formed therein, perforations 105 formed in the plate and in alinement with said slots, resilient arms having their upper ends passed through the slots and terminating in hooks adapted to engage the perforations, said arms being bent intermediate their ends to form eyes, eyes formed 110 upon the lower ends of said arms, upper and

lower flexible frames having snapping hooks carried thereby for engaging the first and second named eyes, respectively to hold said frame stretched in rectangular form, 5 netting connected to the frames and having a skirt formed at its lower edge, a hood having its mouth in communication with the interior of the netting, said hood having its lower edge suspended upon the plane of the

lower edge of the skirt, and sinkers connected to the lower edge of the hood and skirt, as and for the purpose set forth.

In testimony whereof, I affix my signature, in the presence of two witnesses.

ALBERT D. MEAGLEY.

Witnesses:

EDWARD VELER,
CLYDE R. PAINTER.
